US00D840455S

(12) **United States Design Patent** (10) Patent No.: **US D840,455 S**
(45) Date of Patent: **** Feb. 12, 2019**

(54) **LASER LIGHT SOURCE**

(71) Applicant: **FUJIFILM SonoSite, Inc.**, Bothell, WA (US)
(72) Inventors: **Matthew Lider**, Bellevue, WA (US); **Ben Dekock**, Seabeck, WA (US); **Patrick Nally**, Seattle, WA (US); **Tyler Dawson**, Seattle, WA (US)

(73) Assignee: **FUJIFILM SONOSITE, INC.**, Bothell, WA (US)

(**) Term: **15 Years**

(21) Appl. No.: **29/609,915**

(22) Filed: **Jul. 6, 2017**

(51) LOC (11) Cl. **16-99**

(52) U.S. Cl.

USPC **D16/130**

(58) **Field of Classification Search**

USPC D14/137; D16/130, 132, 133, 134, 135, D16/202, 310, 140
CPC G02B 21/0004; G02B 21/22; G02B 21/24; G02B 21/06
